UNITED STATES PATENT OFFICE.

MOSES KATZ, OF DORNA WATRA, AUSTRIA-HUNGARY.

INTEREST-CALCULATOR.

No. 892,526.

Specification of Letters Patent.

Patented July 7, 1908.

Application filed November 28, 1906. Serial No. 345,552.

To all whom it may concern:

Be it known that I, MOSES KATZ, private clerk, a subject of the Emperor of Austria-Hungary, residing in Dorna Watra, Bukowina, Austria-Hungary, have invented new and useful Improvements in Interest-Calculators, of which the following is a specification.

This invention relates to improvements in interest calculating machines designed to calculate the amount of interest due upon a given amount or sum for a given period of time.

The invention will be more fully described in connection with the accompanying drawing and will be more particularly pointed out and ascertained in and by the appended claims.

In the drawing:—Figure 1, is a view in front elevation of a calculator embodying the main features of my invention, said figure showing parts broken away to illustrate internal mechanism. Fig. 2, is a plan view of the same with parts broken away. Fig. 3, is a sectional view on line 3—3 of Fig. 1.

Like numerals of reference designate similar parts throughout the different figures of the drawing.

As shown the calculator comprises a casing, designated as a whole by 1, and having front, rear, end, and top and bottom walls. The front wall, which is designated at 2, is provided in its upper part with a plurality of elongated openings 3 disposed in parallel relation and extending horizontally substantially throughout the length of said wall. Said openings are spaced apart from each other uniformly to provide intervening casting strips 23, there being eleven strips and twelve openings herein shown. The names of the twelve calendar months are disposed opposite said strips at the left of the calculator upon a surface 24 provided for this purpose. On each of said strips alining with the names of the months is disposed a plurality of numerals spaced apart from each other uniformly and extending from points adjacent the names of the months to the right of the casing, said numerals indicating the number of days in each month and being fixed upon a part of the casing and therefore

stationary. Movable means is provided and is associated with said stationary means or strips and there is disposed upon said movable means a plurality of numerals arranged in parallel rows in a manner to be exposed through the openings 3 which numerals range from 1 to 365. Said numerals upon the movable means are disposed in rotation so that the smaller numbers will appear at the left hand extremities of the slots 3 and if desired vertical lines of division may be provided on said stationary and movable means to visually assist the operator in bringing the numbers of the movable means into register with the numbers on the stationary means. As shown said movable means consists of a web 8 trained at its opposite ends about two rollers 7 and inasmuch as said web bears numerals indicating the days or dates it will hereinafter be termed the date web.

Conveniently the casing 2 is divided by a partition 6 and the rollers 7 are mounted in said partition at their lower ends and in the upper wall of the casing at their upper ends. Mechanism is provided for operating said rollers 7 in unison and in the same direction with respect to each other and as shown said means consists of a shaft 9 provided with a crank 11 and bevel gears 10, adapted to mesh with bevel gears 12 which latter are mounted on said rollers. Said shaft 9 is mounted in bearings 25 secured to the top wall of the casing 1. The front wall 2 of said casing is provided with an opening 4 for the purpose of disclosing the dates upon which the loan has been made and a plurality of loaning dates are provided which in the embodiment shown are disposed upon the upper margin of the date web 8 so that the loaning dates will always be maintained in prescribed relation with respect to the dates between the strips 23. The loaning dates on the web 8 consist of the month and day of the month throughout the calendar year. As the numerals on the web 8, which are exposed through the openings 3, indicate the period of time of the loan said numerals will hereinafter be referred to as the time dates and as the numerals on the strips 23 designate the time at which the loan is to be paid, or when interest is to be paid, said numerals will hereinafter be referred to as the payment dates.

The lower portion of the casing is provided on the front wall 2 with a plurality of elongated openings 26 through which are disclosed the sums of interest. Immediately 5 below said openings 26 there is disposed parallel lines of numerals indicating the amount or amounts loaned and said numerals will hereinafter be termed the loaned numerals or indications. There are 10 openings 26 10 shown and 10 commercial rates of interest are designated in columns 27 at the right and left of openings 26 and in registry therewith. Movable means are provided, which as shown are individual with respect to the openings 26, for disclosing the amount of money due 15 as interest and as shown said movable means consists of a plurality of webs 15 mounted upon spring actuated rollers provided with retaining means and on which webs the interest sums or amounts are disposed and said webs will therefore hereinafter be termed interest webs. Each of said webs 15 is provided with a series of numerals designated at 28 to indicate the period of time of the loan. 20 Rollers 29 are mounted abreast of the openings 26 and said rollers are provided with ratchet-wheels 30 and operating knobs 19. Spring pawls 31 engage said ratchet-wheels and prevent the rollers 29 from being rotated 25 after they had been adjusted and before they are leased by said pawls 31. The webs 15 at one end are wound about the rollers 29 and at their other ends about spring actuated rollers 14 which are constructed as follows: 30 Roller spindles 17 are mounted in the end walls of the casing 1 and spiral springs 18 are wound about said spindles and are secured thereto at one end. The ends of said rollers 14 are mounted in sockets 16 which are 35 loosely mounted on said spindles and the opposite ends of said springs are secured to said socket. It will thus be seen that the knobs 19 are turned against the resistance of the springs 18 and that when the spring pawls 31 40 are released the springs 18 will automatically return the webs 15 to a zero position. Guides 22 are provided for the webs 15 and similar guides 13 are provided for the web 8 so as to 45 retain said webs in close proximity to the openings so that the subject matter on said webs will be effectively exposed. As shown only two sets of rollers 14 and 29 are illustrated but it will be obvious that in practice 50 one set will be required for each opening 26. 55 Assuming that it is desired to calculate the interest due on the sum of \$100.00 loaned December 31st, and payable January 11th, (the following year) with interest at 9% the crank 11 will be operated to bring the loaning 60 date December 31st, into an exposing position with respect to the opening 4 and this movement of the web will bring the time date or numeral 11 into registry with the

payable date 11 of the January strip 23 thereby disclosing to the operator the fact 65 that the loan has been made for eleven days. In order to determine the amount of interest due on an eleven day loan of \$100.00 at 9% the operator will rotate the knob 19 adjacent the 70 9% designation in the column 27 until the figure 11 appears in the opening 26 whereupon the operator will refer to the loan numerals below the lowermost slot 26 where he can locate the sum loaned, which in this case is \$100.00, and immediately above this 75 loan indication there will be indicated on the strip 15 the amount of money due as interest which in this case will be \$.27, as indicated above the sum of \$100.00.

I claim:—

1. A calculator comprising in combination a casing provided with fixed means on which payment dates are disposed and an opening for disclosing loaning dates, movable means on which is disposed loaning dates adapted to be exposed through said opening and time dates adapted to be brought in registry with said payment dates, said casing being provided with names of the calendar months opposite said payment dates and with columns bearing rates of interest web openings individual of said rates of interest, loan numerals disposed below said openings, interest webs individual to said openings and bearing interest amounts corresponding to said loan numerals, each web being provided with numerals 28 for indicating the time of the loan, automatic means normally tending to return the webs 15 to a zero position, and retaining means normally preventing the operation of 100 said automatic means.

2. A calculator comprising in combination, a casing provided with fixed means on which payment dates are disposed and an opening for disclosing loaning dates, movable means on which is disposed loaning dates adapted to be exposed through said opening and time dates adapted to be brought in registry with said payment dates, said casing being provided with the names of the calendar months opposite said payment dates and with a column bearing rates of interest, web openings individual to said rates of interest, loan numerals disposed below said openings, and interest webs individual to said openings and bearing interest amounts corresponding to said loan numerals, each web being provided with time loan numerals for indicating the time of the loan.

3. A calculator comprising in combination, fixed means on which payment dates are disposed and means for disclosing one of a series of loaning dates, movable means on which is disposed loaning dates and time dates, said time dates being adapted to be brought in 120 registry with said payment dates, means dis-

closing the names of the calendar months adjacent said payment dates, means disclosing rates of interest, openings individual to said rates of interest, means disclosing loan numerals adjacent said openings, and movable means individual to said openings bearing interest amounts corresponding to said loan numerals, each of said individual movable

means being provided with time loan numerals for indicating the time of the loan. 10

In testimony whereof I affix my signature in presence of two witnesses.

MOSES KATZ.
